UNITED STATES PATENT OFFICE.

ALBIN E. ANDERSON, OF OAKMONT, PENNSYLVANIA, ASSIGNOR OF TWO-THIRDS TO
EYVINA M. VERNER AND JAMES W. MACFARLANE, BOTH OF PITTSBURGH, PENN-
SYLVANIA.

WIRE-ROPE MACHINE.

1,401,122.

Specification of Letters Patent. Patented Dec. 27, 1921.

Application filed April 17, 1920. Serial No. 374,597.

To all whom it may concern:

Be it known that I, ALBIN E. ANDERSON, a citizen of the United States, and resident of Oakmont, in the county of Allegheny and State of Pennsylvania, have invented a new and useful Improvement in Wire-Rope Machines; and I do hereby declare the following to be a full, clear, and exact description thereof.

10 My invention relates to a machine for making wire-rope.

The object of my invention is to provide a machine of this character in which a single flier-frame carries a plurality of individual bobbin-frames, so that smaller cables of a number of strands may be formed on the individual frames to be passed through a twister for combining the individual smaller cables so formed into a larger cable, thereby greatly reducing the floor space required and making a compact machine of this character with large capacity.

To these ends my invention comprises the novel features hereinafter set forth and claimed.

In the accompanying drawings, Figure 1 is a longitudinal elevation of my improved machine; Fig. 2 is an enlarged longitudinal section of a portion of the machine; Fig. 3 is an enlarged end view of the flier frame showing the manner of driving individual frames; Fig. 4 is an enlarged end view of the opposite end of the machine showing the twister heads; Fig. 5 is a plan view of one of the individual bobbin-frames; Fig. 6 is an enlarged view of the main twister head, and Fig. 7 is an enlarged plan view of a portion of one of the individual bobbin-frames.

In the accompanying drawing, the number 2 designates a suitable base upon which the machine is mounted. A shaft 3 is mounted in suitable bearings in the standards 4 and 5. The sleeve 6 incloses a portion of the shaft 3, said shaft being free to rotate in said sleeve. Mounted on one end of the shaft 3 is the gear-wheel 7 which meshes with the pinion 8 on the power-shaft 9 which is driven by any suitable power.

Mounted loosely on the sleeve 6 is the flier-frame 10, said flier-frame being composed of spider-plates 11 and 12 connected together by the bolt-rods 13.

Mounted in the flier-frame 10 are the individual bobbin-frames 14, said bobbin-frames being mounted to rotate on their

own axes. Accordingly, each bobbin-frame has the journal 15 journaled in an opening 16 in the spider plate 11, and to the outer end of said journal is secured the pinion 17. The pinion 17 meshes with the gear 18 on the stub shaft 19 secured to the spider-frame 11. A spur-gear 20 on the sleeve 6 meshes with the gear-wheels 18.

The inner end of each individual bobbin-frame 14 has the trunnion 21 which fits in a bearing 22 in the spider-frame 12. The trunnion 21 has the openings 23 surrounding the central opening 24, said trunnion forming a twister. Bobbins 25 are carried by the bobbin-frame 14, said bobbins being free to rotate freely in said frame on the journals 26, but in order to prevent said bobbins from rotating too rapidly and thereby causing trouble, I provide the springs 27 which act as automatic brakes for said bobbins.

The bobbins 25 carry the wire from which the cable is to be formed, and the bobbin nearest the perforated trunnion or twister 21 has its wire passing through the central opening 24 and said wire forms the core of said cable formed by the individual bobbin-frame. The wires from the bobbins pass through the several openings 23. In the case illustrated, there are seven bobbins in the bobbin-frame, and consequently there are seven openings in the trunnion 21 or twister-plate. Supported by the brackets 27^a are the clamps 28 through which the twisted cable from each individual twister 21 passes, said clamp consisting of the upper and lower clamping members 29 and 30 which are secured together by bolt 31. In order to permit a certain amount of yielding on the part of the clamping members 29 and 30, the rubber pad 32 may be inserted between the washer-plate 33 and the head of the bolt 31.

A second flier-frame 34 may be arranged on the frame 2, said frame being of the same construction as the flier-frame 10 said flier-frame however being keyed by the keys 35 to the shaft 3 so as to be rotated by said shaft. The bolt-rods 13 connect the flier-frame 34 with the flier-frame 10 so that the rotation of the flier-frame 34 by the shaft 3 rotates the flier-frame 10. The flier-frame 34 supports a series of bobbin-frames 36 corresponding in construction to the bobbin-frame 14, but carrying a greater number of bobbins for the reason more fully hereinafter set forth.

The journal 37 of each bobbin-frame 36 has the opening 38 extending through it for the passage of the cable 39 formed by the corresponding bobbin-frame in the flier-frame 10, as clearly illustrated in Fig. 2. 5 Idlers 40 and 41 on the bobbin-frame 36 guide the cable 39 so as not to interfere with the bobbins, and idlers 42 and 43 direct the cable 39 through the central openings 44 of 10 the twister 45. As stated above, the individual bobbin-frames 36 of the flier-frame 34 are greater in number than the bobbins in the bobbin-frame 14 for the reason that sufficient wires have to be provided to cover 15 the core-wire 39 which is the wire formed by the wires from the individual bobbin-frames 14.

In view also of the fact that there are more bobbins in the bobbin-frames 36, it is 20 necessary to rotate said bobbin-frames 36 at a slower rate of speed than the bobbin-frames 14 and accordingly the gear 47 is of smaller diameter than the gear 18, while the pinion 48 is larger than pinion 17, whereby 25 through the gear 47 and the pinion 48, a slower speed is imparted to the bobbin-frames 36.

Clamping members 49 receive the cable from the twister 45 and the cables 50 then 30 pass to the twister-head 51 journaled in the standard 5. The core 52 of the finished cable 53 passes through the passage 54 in the shaft 3.

The finished cable 53 passes around the 35 drum 54 and passes therefrom to a suitable reel, the drum 54 being driven by suitable gearing from the shaft 3.

In the operation of my improved machine, the bobbins 25 in the bobbin-frames 40 14 with a supply of wire thereon are inserted in position in the bobbin-frames, the individual wires thereof being threaded through the openings of the twister 21 and secured in place in the clamps 28. Where 45 a second flier-frame 34 is to be employed, the bobbins in the bobbin-frames 36 being supplied with wire have their wires threaded through the twister 45. As the flier-frames 10 and 34 are rotated, rotary motion 50 is imparted to the individual bobbin-frames of each flier-frame and as the several wires 39 are formed in the bobbin-frames 14 said wires pass to the bobbin-frames of the flier-frame 34 to form the cores for the wires 50 55 formed by said individual bobbin-frames 34. These wires 50 form the outer strands for the finished wire 53 whose core 52 passes through the passage 54 in the shaft 3.

In this manner I provide a machine in 60 which a series of individual bobbin-frames are mounted on a single flier-frame and the wires composed of a number of strands from each bobbin-frame may be fed to a

second flier-frame to be reinforced by a further cover or strands of wires, or if 65 desired the wires from a single flier-frame may pass to a twister 51 to be incorporated in a cable, or as illustrated the second flier-frame may be employed to cover the wires 70 formed in the first flier-frame, the combined wires forming the covering strands for the finished cable 53 which has for its core the hemp or other cable 52. By having a plurality of individual bobbin-frames on a single flier, I am enabled to save a great 75 deal of space and at the same time condense the machine very much thereby reducing the cost of construction and giving a machine of great capacity.

What I claim is:

1. In a machine for making wire cable, the combination of a plurality of axially aligned flier frames connected to rotate together, a plurality of bobbin frames journaled in each of said flier frames, the corresponding bobbin frames carried by the said flier frames being in alignment with each other, means associated with the journals of the bobbin frames carried by the first flier frame for twisting the individual wires into 90 cable strands, means for conducting the said strands through the journals of the next succeeding bobbin frames and for twisting the wires from the bobbins of the second flier frame upon the said strands, and means 95 for thereafter twisting the said strands into a complete cable.

2. In a machine for making wire cable, the combination of two aligned flier frames connected to rotate together, a plurality of bobbin frames carried by each of said flier frames, and each consisting of parallel bars connected at their ends to journals carried by said flier frames, the said bars having means for rotatably mounting a series of individual bobbins, brake members associated with each of said individual bobbins, means for drawing the wires from the said bobbins in each bobbin frame through openings extending through the journals of said bobbin frame, whereby said journals form 100 twisters for twisting said wires into strands, gear wheels carried by the said flier frames, and pinions carried by the said bobbin frames and meshing with the said gear wheels, the said gear wheels and pinions being so proportioned that the bobbin frames carried by the first flier frame are rotated at a higher speed than the bobbin frames carried by the second flier frame. 105 110 115

In testimony whereof, I, the said ALBIN E. ANDERSON, have hereunto set my hand.

ALBIN E. ANDERSON.
